UNITED STATES PATENT OFFICE

164,891

RADIO CABINET

Samuel E. Adler, Chicago, Ill.

Application March 3, 1951, Serial No. 14,380

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio Cabinet, of which the following is a specification, reference being had to the accompanying drawings, forming part thereof.

Fig. 1 is a front elevational view of a radio cabinet, showing my new design, the cover for the dial being in open position;

Fig. 2 is a fragmentary view of the upper portion shown in Fig. 1 but with the dial cover in closed position;

Fig. 3 is a top plan view of the cabinet as shown in Fig. 1; and

Fig. 4 is an elevational view of the right hand end of Fig. 1.

The design of the left side of the cabinet is the same as the right side, and the rear of the cabinet is plain.

The dominant features of my new design reside in that part shown by full lines of the drawings.

I claim:

The ornamental design for a radio cabinet, as shown and described.

SAMUEL E. ADLER.
